EARRING OR SIMILAR ARTICLE

Samuel Dauber, 2634 Burns Place, Union, N.J.

Filed Aug. 30, 1960, Ser. No. 61,950

Term of patent 14 years

(Cl. D45—9)

The design is characterized by the portions shown in solid lines.

I claim:

The ornamental design for an earring or similar article, as shown and described.
